UNITED STATES PATENT OFFICE.

LANSING ONDERDONK, OF WINTHROP, MASSACHUSETTS.

DESIGN FOR A BICYCLE-SEAT SUPPORT.

SPECIFICATION forming part of Design No. 27,359, dated July 13, 1897.

Application filed June 3, 1897. Serial No. 639,355. Term of patent 7 years.

To all whom it may concern:

Be it known that I, LANSING ONDERDONK, a citizen of the United States, residing at Winthrop Beach, in the county of Suffolk, State 5 of Massachusetts, have invented a Design for Bicycle-Seat Supports, of which the following is a description, reference being had to the accompanying drawing, and to the letters of reference marked thereon.

10 My invention relates to a design for bicycle-saddle supports or what are usually known as "T-posts," and the leading feature of the design consists in the shape and configuration of the support or post, as hereinafter described 15 and shown in the accompanying drawing, in which the figure represents in side elevation a bicycle-saddle support embodying my invention.

In the drawing, A represents the shank of 20 the support, which fits within the ordinary seat-post tube of a bicycle. The upper part of this post is provided with an extension B at right angles to it, this extension being rounded at its outer end, as shown at a, and

having a longitudinal opening b. The diameter of the extreme upper part of the bicycle-seat support is of less diameter than that of the shank A, as shown at C, and at its upper end is provided with a horizontal piece c, forming the part upon which the saddle-clamp is fixed, as in the ordinary construction of bicycle T-post. This part c is bent at d, and is provided with a downwardly-extending part e parallel with the part C and shank A, this part e extending down through 35 the opening in the extension B of the shank A, and has upon its lower end an enlarged head f, which is below the plane of said extension B.

I claim as my invention—
The design for a bicycle-saddle support, 40 substantially as shown and described.

In testimony whereof I affix my signature in presence of two witnesses.

LANSING ONDERDONK.
